US00D980177S

(12) **United States Design Patent** (10) **Patent No.:** **US D980,177 S**
(45) **Date of Patent:** **** Mar. 7, 2023**

(54) **CEILING HEATER FOR SUBSTRATE PROCESSING APPARATUS**

(71) Applicant: **KOKUSAI ELECTRIC CORPORATION**, Tokyo (JP)

(72) Inventors: **Shinobu Sugiura**, Toyama (JP); **Tetsuya Kosugi**, Toyama (JP); **Yuya Yoshimura**, Toyama (JP); **Takuto Shoji**, Toyama (JP)

(73) Assignee: **KOKUSAI ELECTRIC CORPORATION**, Tokyo (JP)

(**) Term: **15 Years**

(21) Appl. No.: **29/773,972**

(22) Filed: **Mar. 12, 2021**

(30) **Foreign Application Priority Data**

Sep. 24, 2020 (JP) ..... 2020-020256 D

(51) **LOC (14) Cl.** **13-03**

(52) **U.S. Cl.**

USPC **D13/182**

(58) **Field of Classification Search**

USPC D13/110, 174, 101, 112, 118, 120, 123, D13/133, 146, 147, 159, 154, 156, 199, D13/184, 182; D14/356, 433, 435, 438; D15/144, 144.1, 144.2, 146, 140; D23/314, 322, 333, 415, 417, 499

CPC H01R 24/00; H01R 12/00; H01R 12/70; H01R 13/62

(57) **CLAIM**

The ornamental design for a ceiling heater for substrate processing apparatus, as shown and described.

DESCRIPTION

FIG. 1 is a front, top and right side perspective view of a ceiling heater for substrate processing apparatus showing our new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a rear elevational view.

1 Claim, 4 Drawing Sheets
